UNITED STATES PATENT OFFICE.

WILLIAM H. VOSS, OF DAVENPORT, IOWA.

MECHANICAL MOVEMENT FOR WASHING-MACHINES.

1,079,456.

Specification of Letters Patent.

Patented Nov. 25, 1913.

Application filed January 18, 1913. Serial No. 742,785.

To all whom it may concern:

Be it known that I, WILLIAM H. Voss, a citizen of the United States, residing at Davenport, in the county of Scott and State 5 of Iowa, have invented new and useful Improvements in Mechanical Movements for Washing-Machines, of which the following is a full, clear, and exact description.

My invention relates to mechanism for 10 actuating washing machines, and particularly that class or type of machines having a rotary reciprocable agitator or dolly, a momentum or balance-wheel that assists in the reversal movement of the said agitator, 15 and mechanism adapted to be actuated either manually or through the medium of a suitable motor (electric, gas-engine or other power) for operating the same.

In operating washing-machines of this 20 particular type, it often becomes necessary to stop it instantaneously, or to operate the agitator independently of the wringer, and vice-versa.

It is, therefore, an object of my invention 25 to accomplish these functions in an efficient manner, and at the same time to provide novel mechanism for connecting the operating parts.

Still another object of my invention is to 30 so construct and arrange the various elements of the driving and reversing mechanism that they may all be disposed or mounted below the bottom of the tub or support so that the number of parts to be carried by the top or cover thereof is reduced to a minimum, and said mechanism will be out of the way of the operator.

These and other objects I accomplish by 35 the means and in the manner hereinafter 40 fully described and as particularly pointed out in the claims, reference being had to the accompanying drawings forming a part hereof, in which—

Figure 1 is a vertical side elevation of 45 my invention. Fig. 2 is a similar view of the opposite side thereof. Fig. 3 is a horizontal sectional view taken on line 3—3, Fig. 1, below the plane of the bottom of the tub. Fig. 4 is a detail view of a portion of 50 Fig. 3, drawn to an enlarged scale and having the gear casing removed. Fig. 5 is a detail view of the reversing gears. Fig. 6 is a detail view showing the shifting lever and connected elements. Fig. 7 is a detail

view of a clutch used in connection with my 55 invention. Fig. 8 is a detail view of the locking sleeve for the reversing-gear lever.

The support for my improved mechanism comprises a suitable tub A having the usual hinged cover B in which an agitator-shaft C is journaled, and which rests upon and is elevated above the floor a suitable distance by means of legs D that may be provided with rollers in their lower ends, if desired, which legs are connected together and 60 braced by a rectangular-shaped metallic frame d. The agitator-shaft C is given a rotary reciprocable movement by suitable means E for connecting and transmitting the reciprocable movement of a horizontally disposed rack F to the usual rotary reciprocable motion of said agitator. It is immaterial in what manner the means E are constructed, or of what mechanism the same consist, in so far as the objects of my improvements are concerned. I prefer, however, to employ for this purpose a horizontally disposed gear or pinion mounted on and revolving with the agitator-shaft, but so 65 constructed as to permit the free vertical movement of the latter therein. This mechanism is supported on the lid or cover of the tub, and is, preferably, inclosed within a suitable spherical casing, substantially as shown. This mechanism is a well known 70 mechanical movement and, therefore, need not be illustrated herein. In order to actuate said pinion, a rack F is employed that extends horizontally across the cover to a point beyond the vertical side of the tub and 75 has its outer end removably pivoted to a socket made integral with the upper end of a vertically disposed lever G, of the first class. Said lever is fulcrumed between the lugs projecting outward from a vertically 80 disposed bracket g secured to the side of the tub, and when it is desired to operate my mechanism by hand a handle is inserted 85 in said socket and the lever moved back and forth. The lower end of said lever has a 90 pitman 1 pivotally connected thereto, and this pitman extends to and under the tub, and its opposite end is pivotally connected to a suitable crank 2 that projects from the outer end of a sleeve which latter is loosely 95 mounted on the end of a horizontally disposed drive-shaft 3, that is journaled at one end in the sleeve X of the crank engaging 100 105

bearings 4, and, at the other end in bearings 5 supported upon the frame *d*, hereinbefore mentioned.

Shaft 3 is not directly actuated by crank 2 when the machine is hand driven, but is actuated through the medium of gearing which enables me to utilize the momentum of a speeded up balance-wheel loosely mounted on said shaft. When the machine 10 is actuated by a suitable motor 8, it is done through the medium of a belt 7 directly engaging the balance-wheel, and, in this emergency the gearing referred to imparts a reduced speed to shaft 3.

15 Sleeve *X* of crank 2 extends through bearings 4 and its end portion 19 opposite said crank is increased in diameter and provided with a circumferential groove 20, that is engaged by pins 21 projecting inward from the 20 annular portion of lever 22. The lower end of lever 22 is fulcrumed to a bracket 23 secured to and depending down from the adjacent central reach of frame *d*, and said lever is operated so as to move sleeve *X* 25 longitudinally by means of a bar 24 pivoted to the upper end of the lever and extending horizontally in the same direction as shaft 3. The end of bar 24 opposite lever 22 has two notches 26 in its lower edge, and these notches are adapted to engage an arm 30 27 secured to and projecting from one of the legs of the tub, and hold said lever and sleeve stationary at the inner throw of their movement, or stationary at the limit of 35 the outer movement thereof.

When sleeve *X* is moved to the limit of its inward movement, its inner recessed annular edge 17, which constitutes the female member of a clutch 18, is engaged by the 40 projections 16 on the opposing annular edge of the hub of a gear 15, which is fast on shaft 3. This gear engages and imparts its motion to the small idle-gear 14, which interlocks with a larger idle-gear 11 through 45 the medium of a tenon and groove 13, engagement of the contacting ends of their hubs, and the larger idle-gear 11, engages and actuates the pinion 10, loosely mounted on shaft 3. Pinion 10 has its hub interlocked with the adjacent end of the hub of 50 a fly-wheel 6, and imparts the speeded up movement of gear 15 thereto, and the momentum of this fly-wheel regulates and greatly assists the work of moving the lever 55 back and forth during the operation of the machine.

The hubs of the fly-wheel and of pinion 10 and gear 15 are extended so as to prevent longitudinal movement of the two former between gear 15 and bearings 5 of shaft 3. Idlers 14 and 11, are, preferably, loosely mounted on a stationary shaft 12, and their hubs are likewise extended so as to fill up the space and prevent longitudinal 65 movement thereof between the bosses of the

lower half of the casing *K* within which the ends of shaft 12 are secured and which incloses gears 15, 14, 11 and 10 and is attached to and supported by the frame *d*.

Shaft 3 extends beyond its bearings 5 and has suitable driving and reversing gear mechanism for imparting motion to and for cutting out a wringer mounted on the tub. This gear mechanism, preferably, comprises two idle bevel-gears 30 and 31, that face 70 each other and are loosely mounted on shaft 3 and are normally disengaged therefrom and independently thereof. The teeth of these gears are comparatively small and are spaced as far apart as possible so as to 80 avoid binding of the same during the shifting operation hereinafter described. Rigidly secured to and mounted on drive-shaft 3 between these bevel-gears is the counter-part 32, of a clutch, which is, preferably, cylindrical and is provided with recesses or depressions 33, 33, in its ends that are adapted to be engaged by suitable projections 34 that are made integral with and extend from the adjacent ends of the hubs of bevel-gears 85 30 and 31. Meshing with both bevel-gears 30 and 31 is another bevel-gear 35 that is secured to the lower end of a substantially vertically disposed shaft 36, which latter extends upward to the wringer. The lower 90 end of shaft 36 is journaled in the tubular shank 37 of a spider that has corresponding arms *x*, *x*, projecting in diametrically opposite directions therefrom, whose extremities are turned toward and pivoted to lugs 37^a 95 projecting from the spherical casing that incloses the nest of bevel-gears 30, 31 and 35. This casing, preferably, comprises an upper and a lower hemi-spherical shell 39 and 40, respectively, the latter of which (40) 100 has horizontally alining bearings 41 on its opposite sides through which said drive-shaft 3 passes. Said casing is free to be moved or reciprocated longitudinally on the latter without revolving therewith in order 105 to adapt it to be used to move gears 30 and 31 into and out of engagement with the clutch 32. The fact that the outer ends of the hubs of gears 30 and 31 engage said casing and pinion 35 prevents said gears 110 115 moving toward each other, causes one or the other of said gears to engage clutch 3, when the casing is moved one way or the other in the direction of length of shaft 3, and to take the motion of said shaft, and, 120 as the latter is revolved continuously in one direction during the operating of the machine, one or the other of said gears will drive pinion 35 in one direction and the other gear will drive it in the opposite direction, and the shaft 36 will be thereby rotated 125 and driven either forward or reversed as the case may be, and when neither gear 30 or 31 is engaged by clutch 32 the shaft remains stationary.

In order to bodily move the casing, as just pointed out, I fulcrum the lower end of a rocking-lever 42 (of the first class) to a bracket 43 secured to and projecting outwardly from the adjacent member of frame *d*, and make the upper end 44 of this lever spherical or ball-shaped and seat it in a correspondingly shaped depression or socket 45 on the under side of the lower shell 40 of the casing. This lever 42 is pivotally connected to and is rocked by means of an elongated treadle 46 that extends in a horizontal direction under the tub, and has a foot-plate 46^a on its outer end. Near said foot-plate 10 the treadle is pivotally connected to the outer lower end of substantially crescent shaped bell-crank lever 47. This bell-crank is pivoted adjacent its upper end to a suitable hanger 47^a projecting from frame *d* and has 15 an upwardly pro-lateral extension or arm 48 to the outer end of which an operating rod 49 is secured in any suitable manner, preferably, by a swivel connection. Rod 49 extends upwardly alongside of the tub and terminates at a point slightly below the horizontal plane of the top thereof where it passes up through the bottom of a pocket 50, attached to the side of the tub, and is then bent laterally at substantially right-angles 20 to itself and provided with a handle. This lateral portion extends out through a suitable slot 51 in the shell of said pocket, so that, by raising said handle and then turning it, it will catch on the shoulders of said slot, according as desired. When the foot-treadle 25 is raised or depressed, as the case may be, the gear-casing 40—41 will move so that one or the other of gears 30 or 31 will engage clutch 32. The upper end of bell-crank 47 pivoted to hanger 47^a extends beyond its pivot and a coiled contraction-spring 53 connects the same to the foot-treadle. 30

The upper portion of shaft 36 extends 35 through suitable bearings in a spherical casing 54 and its end inside said casing is provided with a beveled pinion 55 that is in mesh with and drives a beveled pinion 56 secured to the adjacent end of the axle or shaft of the driving roller 57 of a wringer 58 of conventional construction.

In order to accommodate the bearings of the transmission-rod to the slight reciprocation of the gear-casing 40—41, I prefer to 45 connect the upper bearing-sleeve 59 to the casing 54 surrounding the wringer driving gears by means of a universal or swivel joint 60 similar to that illustrated at the lower end of said rod, which it is unnecessary to again describe.

In mounting the motor 8, I prefer to connect two of the supporting legs *D* of the tub by a cross-bar *Y* and swing the motor therefrom by means of brackets *y* that have

eyes in their upper ends through which said 65 bar passes.

Any slack in the belt 7 may be taken up by tapping a hand-screw *y'* through the down-turned flange of the adjacent portion of the frame *d*. 70

After the laundry has been placed in the tub and the cover closed, the motor is started and the mechanism is in the position shown in detail in Fig. 4 of the drawings: that is the clutch 16—17 is disengaged and bars 34 75 on the bevel-gears 30—31 are out of engagement with the clutch member 32. The motor now drives balance wheel 6 and through the train of gearing the main or drive-shaft 3 is actuated at a slower speed than the balance-wheel. In order to operate the agitator shaft *C*, lever 24 is moved inwardly far enough to connect the members of clutch 16—17 thus causing the crank 2 to actuate pitman 1 and rock the operating lever *G* in 80 the well-known manner. When, however, the wringer is to be used, clutch 16—17 is thrown out of engagement (which stops the agitator) and the foot-treadle 46^a, or rod 49, is moved so as to shift the casing 39—40 90 longitudinally on shaft 3. This shifting of the casing will bring the one or the other bosses of gears 30 or 31 into engagement with its respective depression in the clutch counter-part 32 which causes the transmission shaft to revolve and drive the wringer 95 through the gears at its upper end.

What I claim as new is:

1. A mechanical movement comprising a rotary reciprocable shaft and means for 100 driving the same consisting of a motor-driven drive-shaft, a pulley loose on said drive-shaft, a train of speed-reducing gears one of which is connected to said pulley and another of which is fast on said drive-shaft, 105 a crank, means connecting said crank to said last-mentioned gear, and devices operatively connecting said crank to said first-mentioned shaft.

2. A mechanical movement comprising a 110 rotary reciprocable shaft and means for driving the same consisting of a motor-driven drive-shaft, a pulley loose on said drive-shaft, a train of speed-reducing gears one of which is connected to said pulley and 115 another of which is fast on said drive-shaft, a crank loosely carried by said drive-shaft, means connecting said crank to said last-mentioned gear, and devices operatively connecting said crank to said first-mentioned 120 shaft.

3. A mechanical movement comprising a rotary reciprocable shaft and means for 125 driving the same consisting of a motor-driven drive-shaft, a pulley loose on said drive-shaft, a train of speed-reducing gears one of which is connected to said pulley and another of which is fast on said drive-shaft,

- a crank, a clutch mechanism connecting said crank to said last-mentioned gear, and devices operatively connecting said crank to said first-mentioned shaft.
- 5 4. A mechanical movement comprising a rotary reciprocable shaft and means for driving the same consisting of a motor-driven drive-shaft, a pulley loose on said drive-shaft, a train of speed reducing gears one of which is connected to said pulley and another of which is fast on said drive-shaft, a crank, means connecting said crank to said last-mentioned gear, a pitman one end of which is secured to said crank, and devices 10 operatively connecting the opposite end of said pitman to said first-mentioned shaft.
5. A mechanical movement comprising a rotary reciprocable shaft and means for driving the same consisting of a motor-20 driven drive-shaft, a pulley loose on said drive-shaft, a train of speed reducing gears one of which is connected to said pulley and another of which is fast on said drive-shaft, a crank loosely carried by said drive-shaft, 25 means connecting said crank to said last-mentioned gear, a pitman one end of which is secured to said crank, and devices operatively connecting the opposite end of said pitman to said first-mentioned shaft.
- 30 6. A mechanical movement comprising a rotary reciprocable shaft and means for driving the same consisting of a motor-driven drive-shaft, a pulley loose on said drive-shaft, a train of speed reducing gears one of which is connected to said pulley and another of which is fast on said drive-shaft, a crank, a clutch mechanism connecting said crank to said last-mentioned gear, a pitman one end of which is secured to said crank, 35 and devices operatively connecting the opposite end of said pitman to said first-mentioned shaft.
7. A mechanical movement comprising a rotary reciprocable shaft and means for 40 driving the same consisting of a motor-driven drive-shaft, a pulley loose on said drive-shaft, a train of speed reducing gears one of which is connected to said pulley and another of which is fast on said drive-shaft, 45 a crank, a clutch mechanism connecting said crank to said last-mentioned gear, a pitman one end of which is secured to said crank, and devices operatively connecting the opposite end of said pitman to said first-mentioned shaft.
- 50 one end of which is secured to said crank, a lever one end of which is connected to the unsupported end of said pitman, and devices operatively connecting the opposite 55 end of said lever to said first-mentioned shaft.
8. A mechanical movement comprising a rotary reciprocable shaft and means for driving the same consisting of a motor-driven drive-shaft, a pulley loose on said drive-shaft, a train of speed-reducing gears one of which is connected to said pulley and another of which is fast on said drive-shaft, a crank, a clutch one member of which is 60 carried by said crank for operatively connecting said crank to said last-mentioned gear, and devices operatively connecting said crank to said first-mentioned shaft.
9. A mechanical movement comprising a 65 rotary reciprocable shaft and means for driving the same consisting of a motor-driven drive-shaft, a pulley loose on said drive-shaft, a pinion loose on said drive-shaft and actuated by said pulley, a gear 70 fast on said drive-shaft adjacent said pinion, transmission gears meshing with the aforesaid pinion and gear, a crank, means connecting said crank to said last-mentioned gear, and devices operatively connecting 75 said crank to said first-mentioned shaft.
10. A mechanical movement comprising a 80 rotary reciprocable shaft and means for driving the same consisting of a motor-driven drive-shaft, a pulley loose on said drive-shaft, a pinion loose on said drive-shaft and actuated by said pulley, a gear fast on said drive-shaft adjacent said pinion, transmission gears meshing with the aforesaid pinion and gear, a crank loosely 85 carried by said drive-shaft, a clutch mechanism connecting said crank to said last-mentioned gear, and devices operatively connecting 90 said crank to said first-mentioned shaft.
- 95

In witness whereof I have hereunto set my hand this 11th day of January, 1913.

WILLIAM H. VOSS.
